UNITED STATES PATENT OFFICE.

ARTHUR H. McCARREL, OF WASHINGTON, DISTRICT OF COLUMBIA.

COLLAR.

Application filed June 13, 1923, Serial No. 645,178.

To all whom it may concern:

Be it known that I, ARTHUR H. McCARREL, a citizen of the United States, residing at Washington, in the District of Columbia, have invented a new and useful Collar, of which the following is a specification.

This invention relates to the manufacture of collars of the soft or semi-soft turned-down type.

10 The general object of the invention is to produce a collar of the type specified, which can be laundered without the aid of starch, and which, when ironed and ready for wear, will readily fold along a predetermined line, 5 while the portions on each side of this line will be of uniform stiffness throughout. This curved line, which is more flexible than the remainder of the fabric, is secured by beating up each separate pick of the filling 20 threads by means of a curved reed, so that they extend across the fabric in parallel arcs, and periodically changing the weave or the filling, or both the weave and the filling, for a sufficient number of picks to form the desired arcuate fold line. The change in weave is effected by a change in the manner of shedding the harness so that the fabric along this line is made more flexible, but not weakened; and the change in filling may 25 be effected by shifting the shuttle boxes. The fabric is woven in suitable widths so that the collars are cut transversely of the fabric; in other words, the filling threads run lengthwise of the collar, while the warp threads run transversely thereof and form the hinge upon which the collar is folded. Since there are considerably more warp 30 threads to the inch than there are filling threads, the collar on the fold line, where the greatest wear occurs, will be more durable than if the fold ran lengthwise of the fabric.

It is preferred to manufacture the collar from a fabric which is specially woven and 15 formed of an upper ply cloth and bottom cloth, spot bound at intervals so that the collar blank, after being cut out, may be separated to the required depth around its periphery by the insertion of a cutting knife, 20 into two separate strips which are inturned and hemmed to form a collar with perfect edges, and which will be the same on both sides. The collar when so made may be formed with integral tabs, or separate tabs 25 may be inserted between the folded-in edges

and stitched simultaneously with the stitching of the edges.

For a more complete exposition of the weaving of the special fabric from which the improved collars are manufactured, and of the loom of special construction by means of which the fabric is woven, reference may be made to my co-pending applications filed June 13, 1923, Serial Numbers 645,180 and 645,179.

60 The invention which forms the subject matter of the present application will be understood from the following detailed description taken in connection with the accompanying drawings, which illustrate the invention in its preferred form.

In the drawings:

Figure 1 is a perspective view of a completed collar, constructed in accordance with my invention.

75 Figure 2 is a plan view of a piece of fabric with a plurality of collar blanks marked out thereon.

Figure 3 is a diagrammatic view showing the course of the warp threads through one 80 style of fabric from which collars may be manufactured.

Figure 4 is a similar view of another type of fabric, specially designed for the purpose of the invention.

85 Figure 5 is a plan view, with a portion shown in section, of a collar blank prepared for hemming.

Figure 6 is a detailed sectional view showing the manner of preparing the edges of the 90 blanks.

Figure 7 is a detailed sectional view showing the edge of the collar completed.

Figure 8 is a similar view showing the manner of attaching a separately prepared 95 tab.

Figure 9 is a detailed plan view of a portion of a collar having an integrally formed tab.

The special fabric, illustrated in Figure 2, 100 the manufacture of which is more particularly described in the above mentioned application, Serial Number 645,180, is woven as shown with the warp threads running straight, lengthwise of the fabric, and with 105 the filling threads running across the fabric in parallel arcs, having a radius of about six feet, in order to conform closely with the curvature of the line upon which the collar is to be folded. The fabric is sufficiently 110

wide so that the collar blanks may be cut transversely thereof leaving sufficient margin for the turning in and finishing of the edges, and for the integral tabs if such are desired. For the manufacture of a standard number 15 collar, a fabric about eighteen inches wide is required. The fabric is made up of a succession of patterns, each including a narrow curved strip or fold line 10 conforming to the curvature of the filling threads, and which is of a different weave or construction from the remainder of the pattern. The width of this strip is of a sufficient number of picks to form the desired fold line of the collar, and these special strips are so woven that the fabric will be more flexible along this line than elsewhere. The collar blanks are then marked off and cut on the line 11 in such a manner that the strip 10 will traverse the blank longitudinally on the line where the collar should be folded.

The principles which govern the weaving of these patterns will be understood from Figures 3 and 4. A fabric woven as indicated in Figure 3 includes an upper ply formed by the warp threads A and B, woven one up and one down, and filling threads W, while the lower ply consists of warp threads C and D and filling threads W woven in a similar manner. In the weaving, these two plies are stitched together by binding threads K, which run alternately over and under the successive filling threads of the upper and lower plies, and between the two plies run the gut threads G. When it is desired to change the weave so as to form the narrow strip 10, the harness is shifted in a different manner and each binding thread K runs with a warp thread C, and each gut thread G runs with a warp thread D, thus forming two plies which are entirely separate throughout the width of the strip, so that they offer less resistance to the folding strain than is offered by the main portion of the fabric in which the binding thread runs alternately above and below the successive filling threads of each ply. In this narrow strip, a filling thread of different character may be used if desired, this being effected by shifting the shuttle boxes in a manner well known to those skilled in the art. After a strip of a predetermined number of picks has been thus woven, the weave is then changed back to that previously described.

In the diagram shown in Figure 4, the normal weave consists of an upper two-ply cloth woven from the warp threads A, B, C, D and K and filling threads W in the same manner as the fabric shown in Figure 3 and also includes a single plain bottom cloth woven from the warp threads M and N and filling threads W. The upper and lower cloths are woven separately from each

other except that periodically the gut thread G is dropped down into the lower fabric for one pick to spot-bind the two fabrics together. The special fold line in this fabric is woven in the same manner as that shown in Figure 3 with the gut thread following the thread A, and the knitting thread following the thread C, while the threads M and N of the lower cloth continue in the same manner as before.

The style of weave illustrated in Figure 4, in which the two-ply upper cloth is woven separately from the single plain bottom cloth except for the spot-binding effected by the gut thread G, is designed for a special purpose. The binding stitches of the gut thread will be close enough together to give the fabric the appearance of the usual three-ply fabric, in which the several plies are all closely bound together, but it has the advantage that by cutting the gut threads where they pass between the upper and lower cloths, the fabric may be separated into two separate cloths, the spot binding in the fabric in the space between the patterns being so varied as to readily admit of the insertion of the separating knife.

A fabric woven as illustrated in Figure 3, consists of a double ply woven cloth, the upper and lower plies being bound together on each pick by the binding thread as shown, and also containing a gut thread, not binding with the plies, but lying between them with the sole object of adding body to the fabric. It will be noted therefore that this fabric is not separable into its component plies, as is the case with the fabric illustrated in Figure 4.

In the manufacture of collars from the fabric illustrated in Figure 3, the collar blanks are stamped out oversize, and the edge of the fabric is then turned over on itself, and then stitched and bound with finishing tape, the collar being made from a stamped blank, either with integral tabs or with detached tabs. This is the usual method heretofore used in finishing collars, which have always been constructed from ply fabrics which are not separable. The construction of collars from the fabric illustrated in Figure 3 according to the present invention however, is a distinct improvement over the former method, in that the blanks are so stamped that the narrow curved strip 10 forms the fold line, and the warp threads run transversely across the same.

In manufacturing the collars from fabric woven as illustrated in Figure 4, the blank 12 is separated along its edge, as shown at 13, by cutting the binding stitches of the gut threads with a sharp knife. The edges 14 and 15 are then folded inwardly upon themselves and hemmed by machine stitching, as shown at 16, thus bringing the collar

to the right size, and at the same time finishing the same from the one blank, with perfect edges. Thus it will be seen, that a collar so produced will be of perfect finish without the use of tape and will also be reversible.

As shown in Figures 5 to 8, the tabs 17 are cut and prepared separately and inserted into the ends of the collar, and 10 stitched at the same time that the latter is hemmed. The collars may also be made with integral tabs.

In turned-down, semi-soft collars as heretofore made from a single piece of fabric 15 stamped out from a blank, the blank is cut over size and the raw edges thereof are turned over and bound with tape and secured by stitching, in some cases the raw edges being previously whip-stitched. In 20 such collars where the tabs are a part of the original blank concave corners are developed at the point indicated at 18, Figure 9. In the attempt to complete and finish such collars with the added edge tape, it is impossible to make a neat job of the return of the tape in such concave corners. Then, too, these corners are exposed in the wearing of the collar, and so is the tape on the reverse side of the neck band at this point. These 30 defects are unsightly and detract from the appearance of the collar when being worn. It is with a view to overcoming this trouble in hemming around the concave corners, and further with a view to making these corners 35 sharp and distinct, as they should be, that the blanks are stamped out as outlined above; and in hemming around the edges, separate and detached tabs, previously prepared, are inserted between the plies of the 40 fabric and become fastened in place in the hemming above referred to in connection with Figures 5 to 8. The tabs thus become a part of the unit collar. It will be seen, however, upon reference to Figure 9 that the collar blank may be stamped out with 45 integral tabs 19, and the edges finished by inturning and stitching in the manner which I have devised, with results far superior to those heretofore obtained with integrally 50 formed edges bound by tape.

The claims of the present application are directed particularly to a collar having a curved fold line, the fabric being woven and the collar being cut in such a manner that 55 the warp threads run transversely across said fold line and the filling threads follow the curvature thereof. Claims specifically directed to the spot-binding and the manner in which the marginal edge of the collar is 60 formed will be presented in a separate application.

Most of the semi-soft, one-piece collars, now on the market, are made from conically woven narrow fabrics, in which the threads 65 of warp yarn, which greatly exceed the num-

ber of filling picks, run lengthwise of the collar. In the use of such collars the stress in folding falls mainly upon the filling threads where they cross this line. In collars made according to the special method 70 herein described, however, the folding stress will fall upon the warp threads where they cross through the line, and the collars so made will be much more durable. The warp threads run in parallel straight lines, while 75 the filling threads run in parallel arcs, so that the density is uniform throughout the fabric, the ends per inch as well as the picks per inch remaining uniform, whereas in a conically woven fabric the density varies 80 across the width of the fabric, being greatest on the inner edge and least on the outer edge, due to the radial position of the picks in such conically woven fabric. By manufacturing collars as herein described, therefore, from a flat fabric of uniform density, and having none of the internal stresses which are created by the conical take-up motion, many difficulties in the subsequent treatment of the fabric are obviated, and 85 the expense of manufacturing the collar is materially reduced.

It is to be understood, however, that the special weaves herein described are merely for the purpose of illustration, and that the same may vary both in the manner of shifting the harness and in the character of the threads used in weaving. It is my intention, therefore, to include all such variations both in the weaving and in the method of 90 manufacturing the collar, as fall within the scope of the appended claims.

What is claimed is:—

1. As an article of manufacture, a turned-down collar having a curved fold line and 100 made from a closely woven multiply fabric in which the warp threads run transversely across the fold line, and the filling threads follow the curvature of said fold line, the number of warp threads and filling threads 110 to the inch being uniform throughout the collar.

2. As an article of manufacture, a turned-down collar having a curved fold line and 115 made from closely woven multiply fabric in which the warp threads run transversely across the fold line, and the filling threads follow the curvature of said fold line, said fold line having the same strength but of different weave and more flexible than the 120 remainder of the collar.

3. As an article of manufacture, a one-piece turned-down collar made from multiply fabric with a curvilinear fold line having a filling thread of different character 125 than the remainder of the collar, said fold line having greater flexibility than the rest of the collar, the number of warp threads and filling threads to the inch being uniform throughout the collar.

4. As an article of manufacture, a one-piece turned-down collar made from multiply fabric with a curvilinear fold portion of greater flexibility, of a different weave, and having a different filling thread from the rest of the collar, the number of warp threads and filling threads to the inch being uniform throughout the collar.
5. As an article of manufacture, a turned-down collar made of multiply fabric with the warp threads running transversely across the fold portion of the collar, said fold portion being of distinctive weave and more flexible than the remainder of the collar, the number of warp threads and the number of filling threads per inch being uniform throughout the collar.
6. As an article of manufacture, a turned-down collar made of multiply fabric and having a curved fold line with the warp threads running transversely across the same, and the filling threads following the curvature of said fold line, certain of the plies being periodically bound together throughout all portions except at the fold line of the collar, so as to form a unitary fabric,
7. As an article of manufacture, a turned-down collar made of multiply fabric having a curvilinear fold portion with the warp threads running across the fold portion and the filling threads following the curvature of the fold portion, certain of the plies being periodically bound together throughout all except the fold portion of the collar so as to form a unitary fabric, said plies being separate from each other at the fold portion with the binding threads crossing said fold portion side by side with the warp threads, so that each ply of the fold portion bends independently of the other, thus rendering the fold portion more flexible but no weaker than the rest of the collar.

In testimony, that I claim the foregoing as my own, I have hereto affixed my signature.

ARTHUR H. McCARREL.
